ALVA S. MERRIETT, OF LOS ANGELES, CALIFORNIA.

APPARATUS FOR FORMING CONCRETE STRUCTURES.

1,137,998.

Specification of Letters Patent.

Patented May 4, 1915.

Application filed November 3, 1913. Serial No. 798,941.

To all whom it may concern:

Be it known that I, ALVA S. MERRIETT, a citizen of the United States, residing at Los Angeles, in the county of Los Angeles 5 and State of California, have invented certain new and useful Improvements in Apparatus for Forming Concrete Structures; and I do declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

My invention relates to an apparatus for forming concrete structures, and more particularly to forms for use in making concrete walls, the principal object of the 20 invention being to provide a clamp which may be carried on the wall forms and attached to tie rods by which the forms are connected, to hold same in spaced relation while a wall is being poured. In accomplishing this object I have provided the improved details of structure hereinafter described and illustrated in the accompanying drawings, wherein:—

Figure I is a side elevation of a portion 30 of a wall form, showing the method of using my improved clamp. Fig. II is a cross-section on the line II—II, Fig. I. Fig. III is an enlarged perspective view of a clamp and the wall form members to which 35 the clamp members are attached. Fig. IV is a detail perspective of one of the clamp ears, showing the outer face of the ear. Fig. V is a similar view, showing the inner face of the ear. Fig. VI is a longitudinal 40 section of a tubular cross-bar and one of the clamp ears, with its bracket. Fig. VII is an interior perspective of part of a wall form, illustrating a slip joint for the form members. Fig. VIII is a perspective view 45 of inner and outer clip joint members.

Referring more in detail to the parts:— 1 designates sections of a wall form, each of which comprises a wood frame 2 having a sheet metal covering 3, and having notched 50 corners 4 for receiving the cross or tie bars 5, which are preferably tubular.

Fixed in each corner of each form section is a cast bracket 6, having a slot 7 for receiving a bolt, or the like, 9, by which clamp- 55 ing ears 10 are attached to the bracket.

Each of the clamping ears 10 comprises a head 11, having a slot 12 adapted to overlie a bracket slot 7, a flange 13 for spacing the head from the bracket and forming a chamber 14 for containing a nut 15, and ribs 16 60 for bracing the head laterally from the face of the bracket.

Integral with the head 11 and spaced from the plane thereof, by a neck 18, is a body portion 19, having a hook 20 thereon, 65 comprising a shank 21, having a tip 22 adapted for projection into a socket 24 in the cross bar 5.

The bolt member 9 comprises a head 26, which is adapted to bear against the outer 70 face of the head 11, a shank 27 which is adapted for projection through the clamp slot 7, the chamber 14, and the bracket slot 7, the nut 15, whereby the shank 27 is attached to the clamp head, and a wing nut 29, 75 whereby the shank is attached to the form bracket.

In order that the clamps may be used when the joints of the forms are broken, that is, when the ends of form members in 80 one tier abut beneath the center of a form member in an upper tier, or vice versa, I mount one of the brackets 6 at the center of each frame 2, so that a clamp member may be mounted thereon and coöperate with the 85 corner members in an adjacent tier to form a triangular clamp that will hold the form members in place, and spaced from their opposite members. I also prefer to provide each of the clamp members with an aperture 90 30, so that it may be applied to a hook 31 on the form and attached thereto to be carried on the form when the latter is not in use, and be readily at hand when needed.

In order to adapt the forms for use in 95 making different length walls, I provide a slip joint for the form members, comprising plates 33, having laterally turned edge lips 34 provided with inturned flanges 35, forming grooves 36, within which the ends 100 of the form members 1 may be projected; it being apparent that the form members may be arranged end to end to form the body of the wall, but that should the desired length or width of the wall be such 105 that a short length form might be required to complete it, one or more of the slip joints may be used to give the form proper length by extending ends of adjacent forms partially into the slip joints: 110

The slip joints are usually and preferably used at the corners of the form, and in order to properly fill the corners, I fasten rails 38 at the ends of the joint members and place a block 39 in the corner of the form and bolt same to the rails, so that the inner corner may be formed at a right angle, the blocks being preferably raised above the upper end of the forms, so that 10 the upper tier of forms may abut thereagainst.

Presuming the form members to be constructed as described, with the brackets fixed thereon at angle corners and in the 15 center, when a form is to be set up, the members are arranged in spaced relation and in tiers, with the joints broken in succeeding tiers, as illustrated.

In spacing the form members to form a 20 pouring space therebetween, the cross bars are seated in the corner notches of the lower tier, and the hooks on the ends of the clamp ears projected into proper apertures in the cross bars and secured to the form brackets 25 by projecting the bolts through the bracket slots and tightening the wing nuts against the inner faces of the brackets. When two or more tiers have been arranged and connected in this manner, material is poured 30 into the space between the form members and allowed to set or harden. When the lower portion of a wall has been formed in this manner, the lower form members may be removed by loosening the wing nuts, 35 removing the clamp ears from the cross bars and removing the form members from the face of the walls; the cross bars being pulled out of the wall and the apertures left by the withdrawal of the cross bars being filled 40 with cement. When the lower form members have been removed, they may be applied at the upper position in like manner and the process continued until the wall has been built up to the proper height. 45 When the wall has been completed and the form members are to be moved, or stored, the clamp ears are placed over the hooks 50 and the latter given a part turn in order to lock the ears in place, so that they cannot be lost from the form members, but are carried therewith to be readily at hand when the members are to be moved to a new job.

While form members of different length 55 may be provided for forming walls of variable length, I prefer to utilize the slip joints heretofore described, it being apparent that the ends of the forms may be projected into the slip joints a greater or less distance as necessary, to provide a form of proper length; thereby obviating the necessity for form members of different lengths.

Having thus described my invention, what I claim as new therein, and desire to secure by Letters-Patent, is:—

65 1. The combination with form members,

of brackets fixed on each corner of said form members, a cross bar, and clamps removably mounted on said brackets and adapted for application to the cross bar, for the purpose set forth. 70

2. The combination with form members, of brackets fixed on each corner of and near the center of the longitudinal edges of said form members, a cross bar, and clamps removably mounted on said brackets and 75 adapted for adjustable application to the cross bar, for the purpose set forth.

3. The combination with form members having corner notches and brackets fixed in the corners on said members adjacent the 80 notches, a cross bar adapted to seat in said notches, and clamp members mounted on said brackets and adapted for adjustable connection with said cross bar.

4. The combination with form members 85 having corner notches, of brackets mounted in the corners and at intermediate positions on said members, a cross bar adapted to seat in said notches, and clamp members adapted for mounting on said brackets and for engagement with said cross bar.

5. The combination with form members having corner notches, of a cross bar adapted for support in the corner notches of said form members and provided with sockets, 95 and clamp members carried by the form members and having tips adapted for projection in the sockets in said cross bar.

6. The combination with form members having slotted brackets thereon, of a cross 100 bar, clamp members adapted for connection with the cross bar, bolts mounted on the clamp members and adapted for projection through the bracket slots, and nuts on said bolts adapted for engaging the brackets, for 105 the purpose set forth.

7. The combination with form members having slotted brackets, of a cross bar, clamp members adapted for connection with the cross bar and having slotted heads adapted 110 to overlie the slotted portions of said brackets, bolts attached to said clamp members and adapted for projection through the bracket slots, and wing nuts on said bolts for tightening the clamp members against 115 the brackets.

8. The combination with form members having brackets thereon, of a cross bar, a clamp member adapted for connection with the cross bar and having a head provided 120 with a chamber and with a slot opening into said chamber, a bolt projected through the slot and chamber, a nut on said bolt within the chamber, and means on said bolt for attaching the clamp head to said bracket. 125

9. The combination with a form member having a bracket thereon, of a cross bar, a clamp member comprising a slotted head having flanges for spacing the head from said bracket, a bolt extending through the 130

head slot and between said flanges, a nut on said bolt between the flanges for attaching the bolt to said head, and a nut on the inner end of said bolt for attaching the head to 5 said bracket.

10. The combination with a form member having a bracket thereon, of a cross bar, a clamp member comprising a slotted head having flanges for spacing the head from 10 said bracket, a bolt extending through the head slot and between said flanges, a nut on said bolt between the flanges for attaching the bolt to said head, a nut on the inner end of said bolt for attaching the head to said 15 bracket, and lips projecting laterally from said flanges and bearing against said bracket.

11. The combination with form members having corner brackets and a bracket near 20 the center of each longitudinal side, of a cross-bar having a plurality of apertures arranged in spaced planes perpendicular to the axis of the bar, and clamp members connected with each bracket and having outer 25 turned hooks adapted for projection into each of the apertures of one plane of the cross-bar.

12. The combination with form members having corner notches, and brackets secured 30 within each corner of said form members opposite said notches, of an apertured cross-bar adapted to seat in said notches, and clamp members secured to said brackets and adapted for projection into the apertures of 35 said cross-bar.

13. The combination with form members, of a sliding section comprising a plate having inwardly opening edge grooves adapted 40 for sliding contact with the edges of the form members, and a stiffening bar secured to one edge of the plate and within the edge grooves.

14. The combination with form members of equal length, of sliding sections comprising plates having edge grooves for receiving 45 said form members and stiffening members at one end, a corner post, means for attaching the stiffening members of the sliding sections to the corner posts to form a corner 50 mold, whereby the ultimate length of a series of form members may be varied by the

position of the sliding sections upon the last of the series of form members.

15. The combination with form members of equal length, of sliding sections comprising plates having edge grooves for receiving 55 said form members and stiffening members at one end, a corner post equal in length to the width of the sliding section plates, and means for attaching the stiffening members to said post, so that the post projects beyond the edge of the sliding sections to determine positively the position of succeeding sections.

16. The combination with form members 60 of equal length, of sliding sections comprising plates having edge grooves for receiving said form members and stiffening members at one end, a corner post equal in length to the width of the sliding section plates, and 65 means for attaching said stiffening members to said post in offset relation to form projection and depression joint portions which are adapted for coöperation with similar portions of adjoining sections to aline the mold. 70

17. The combination with form members having slotted brackets, and an apertured cross-bar, of clamp members comprising body members having offset hook members 75 adapted to bear against said form member and engage said apertured bar, and bolts in said body members adapted for coöperation with said slotted brackets to draw said body against the form and exert a leverage on 80 said bar.

18. The combination with form members having slotted brackets and an apertured cross-bar, of clamp members comprising body portions having offset hook portions provided with outturned tips adapted for 90 coöperation with said apertured bar, and bolts in said body portions adapted for coöperation with said slotted brackets to draw said body portions against said form and exert a leverage on said bar. 95

In testimony whereof I affix my signature in presence of two witnesses.
